US00D809477S

(12) **United States Design Patent** (10) **Patent No.:** **US D809,477 S**
Brunner et al. (45) **Date of Patent:** **** Feb. 6, 2018**

(54) **HEADSET**(71) Applicant: **Apple Inc.**, Cupertino, CA (US)(72) Inventors: **Robert Brunner**, San Francisco, CA (US); **Christopher Kuh**, San Francisco, CA (US)(73) Assignee: **Apple Inc.**, Cupertino, CA (US)(***) Term: **15 Years**(21) Appl. No.: **29/568,227**(22) Filed: **Jun. 16, 2016****Related U.S. Application Data**

(60) Continuation of application No. 29/527,761, filed on May 21, 2015, now Pat. No. Des. 760,688, which is a continuation of application No. 29/490,833, filed on May 14, 2014, now Pat. No. Des. 732,503, which is a continuation of application No. 29/471,109, filed on Oct. 28, 2013, now Pat. No. Des. 709,860, which is a division of application No. 29/410,584, filed on Jan. 9, 2012, now Pat. No. Des. 692,410.

Primary Examiner — Paula Allen Greene*(74) Attorney, Agent, or Firm* — Sterne, Kessler, Goldstein & Fox P.L.L.C.(57) **CLAIM**

The ornamental design for a headset, as shown and described.

DESCRIPTION

FIG. 1 is a front perspective view of a headset showing the claimed design;

FIG. 2 is a rear view thereof;

FIG. 3 is a bottom view thereof;

FIG. 4 is a front view thereof;

FIG. 5 is a right side view thereof; and,

FIG. 6 is a left side view thereof.

The broken lines in the figures show portions of the headset that form no part of the claimed design.

1 Claim, 6 Drawing Sheets# US D809,477 S
